US00D769199S

(12) **United States Design Patent** (10) Patent No.: **US D769,199 S**
Chen et al. (45) Date of Patent: **** Oct. 18, 2016**

(54) **LIGHT-EMITTING DIODE UNIT**

(71) Applicant: **EPISTAR CORPORATION**, Hsinchu (TW)

(72) Inventors: **Chao Hsing Chen**, Hsinchu (TW); **Tsung Hsun Chiang**, Hsinchu (TW); **Chien Chih Liao**, Hsinchu (TW); **Wen Hung Chuang**, Hsinchu (TW); **Bo Jiun Hu**, Hsinchu (TW); **Tzu Yao Tseng**, Hsinchu (TW); **Jia Kuen Wang**, Hsinchu (TW); **Tsun Kai Ko**, Hsinchu (TW); **Chien Fu Shen**, Hsinchu (TW); **Kuan Yi Lee**, Hsinchu (TW); **Min Yen Tsai**, Hsinchu (TW)

(73) Assignee: **EPISTAR CORPORATION**, Hsinchu (TW)

(**) Term: **14 Years**

(21) Appl. No.: **29/526,403**

(22) Filed: **May 8, 2015**

(30) **Foreign Application Priority Data**

Nov. 10, 2014 (TW) 103306536

(51) LOC (10) Cl. **13-03**

(57) **CLAIM**

The ornamental design for a light-emitting diode unit, as shown and described.

DESCRIPTION

FIG. 1 is a perspective view of a light-emitting diode unit showing our new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken line showing is for the purpose of illustrating environmental structure only and forms no part of the claimed design.

1 Claim, 6 Drawing Sheets
